UNITED STATES PATENT OFFICE.

LINUS T. FURNAS, OF LIMA, OHIO.

CORSET-COVER.

1,086,153.

Specification of Letters Patent. Patented Feb. 3, 1914.

Application filed June 6, 1912. Serial No. 702,063.

To all whom it may concern:

Be it known that I, LINUS T. FURNAS, a citizen of the United States, and a resident of Lima, in the county of Allen and State 5 of Ohio, have invented a new and Improved Corset-Cover, of which the following is a full, clear, and exact description.

The invention relates to a new and improved garment in the form of a corset cover 10 or brassière which is adapted for contraction or expansion at both top and bottom and intermediately on a vertical median line for giving a desired contour to the bust and waist.

15 A practical embodiment of the invention is represented in the accompanying drawings forming a part of this specification, in which similar characters of reference indicate corresponding parts in all the views.

20 Figure 1 is a front elevation of the garment as applied; Fig. 2 is a rear elevation of the same; Fig. 3 is an elevation of the upper front portion of the garment showing the top adjusting means in open position; Fig. 25 4 is a similar view of the lower front portion of the garment showing the waist-adjusting means; and Fig. 5 is an elevation of the lower rear portion of the garment.

25 The body A of the garment is provided 30 with a continuous front B and shoulder straps C, and the rear of the body A is open and is provided at the lower rear corners with tying strings D adapted to be passed around the waist of the wearer over the 35 corset E to be tied into a knot D' at the front, as plainly indicated in Fig. 1. It is understood that the rear ends of the body A are crossed or overlapped at the rear, as indicated in Fig. 2. The front B is cut out at

40 F and strings G are attached to the upper corners of the cut out to permit adjustment of the side edges and corners closer together or farther apart according to the wearer's figure. The front B is also cut out at the

45 lower portion on the median line, thus forming a V-shaped opening H. A tape I, forming part of the waist-band of the garment, extends across the lower opening H, as 50 plainly indicated in Fig. 4, and on the said tape I is slidably mounted a downwardly-extending buckle strap J carrying an adjustable loop J' adapted to hook onto one of the studs E' of the corset E at the busks thereof,

55 as plainly indicated in Fig. 1. Thus by the arrangement described the garment is drawn downward at the waist line, and at the same

time the lower points of the cut-out portion H are drawn inwardly together to the extent that the size of the waist will permit, causing the garment automatically to adapt itself 60 to any ordinary size of waist. Strings K are also attached to the side walls of the cut-out portion H near the lower end thereof, enabling the wearer further to draw in the garment in case of an extremely small 65 waist, thus taking up all surplus size at the waist line in every instance. It is understood that the strings G and K are tied with bows after the desired adjustments are made.

The front B of the body A is provided at 70 the sides with reinforced bands B' extending from the waist, adjacent the cut-out portion H, upwardly to the neckband to one side of the top cut-out portion F, as plainly indicated in Fig. 1. A cross band or plait B² 75 connects the side bands B' with each other at the apex of the cut-out portion F, and another cross band or plait B³ connects the side bands B' with each other a distance downward from the cross band B² so as to 80 leave a shirring portion B⁴ between the said cross bands B² and B³. The sides of the shirring portion B⁴ terminate at the corresponding portions of the side bands B'. The shirring portion B⁴ is provided at the me- 85 dian line with slots or beadings B⁵ engaged by shirring strings L, of which one is secured at one end to the cross band B² and the other is secured at one end to the cross band B³. The shirring strings L are adapted to be tied 90 into a bow at the middle of the shirring portion B⁴ so that on drawing the shirring strings L more or less together the portion B⁴ is shirred more or less in an up and down direction. The purpose of this is as follows: 95 When the walls of the cut-out portion H are drawn together by hooking down the strap J or by tying strings K, there is produced a longitudinal surplus of material along the walls and immediately above the apex of the 100 same, destroying the fit of the garment. This is also true in less degree of the cut-out portion F at the top. By drawing the shirring strings L the surplus is taken away both at the top and bottom and consumed 105 in the shirring portion B⁴ where it also provides to an exact degree the extra rotundity required by a bust that is proportionately large for the waist.

From the foregoing it will be seen that all 110 adjustments are provided at the median line of the front of the garment at the top, at

the bottom and immediately below the top adjustment, and the top and bottom adjustments permit of drawing in or letting out in a sidewise direction, while the intermediate 5 adjustment of the shirring portion B^4 permits an up and down drawing in or letting out of the corresponding portion of the garment, so that the latter can be readily adjusted to any shaped figure irrespective of 10 the relative sizes of waist and bust.

It will be noticed that in case the waist of the wearer is quite large in proportion to the bust then the two sides of the bottom cut-out portion H stand apart a sufficient 15 distance to fit the garment to the size of the waist, and if the waist is abnormally large the cut-out portion readily permits opening up to fit itself to the size perfectly, and likewise the bottom adjustment perfectly 20 adapts itself to any size of waist between the exceedingly large and the small.

By the arrangement described the garment draws correctly over the bust where the figure needs confining.

25 Having thus described my invention, I claim as new and desire to secure by Letters Patent:

1. A garment of the character described, comprising a body which has front alined 30 openings at both top and bottom, and pro-

vided intermediately and directly below the top opening with a shirred portion, and strings applied for closing the two openings and also contracting the shirr more or less, as and for the purpose specified. 35

2. A garment of the character described, comprising a body open at the rear and continuous at the front, the front having along its median line a V-shaped cut-out portion at the top and an inverted V-shaped cut-out 40 portion at the waist, a waistband at the lower margin of the said body and extending across the wide gap of the waist cut-out portion, a buckle strap depending from the said waistband at the waist cut-out portion, 45 sets of strings connected with the front at the sides of the top and waist cut-out portions, and shirring strings interlaced with the upper portion of the front immediately below the said top cut-out portion, the said shirring strings being arranged to shirr the 50 said front upper portion in an up and down direction.

In testimony whereof I have signed my name to this specification in the presence of 55 two subscribing witnesses.

LINUS T. FURNAS.
